UNITED STATES PATENT OFFICE.

ARCHIBALD M. ESTABROOK, OF HAVERHILL, MASSACHUSETTS, ASSIGNOR OF ONE-HALF TO THADDEUS F. TYLER, OF HAVERHILL, MASSACHUSETTS.

DOORKNOB SCREW.

Application filed January 25, 1926. Serial No. 83,709.

This invention relates to builders' hardware and pertains particularly to a new type of screw designed for use in connection with door knobs.

5 The primary object of this invention is the provision, in a manner as hereinafter set forth, of a screw so formed that upon being forced to position a deformation will take place which will act to lock the screw 10 against accidental loosening or misplacement.

The invention contemplates the provision 15 of a screw designed for use in securing door knobs to their spindles, in such a manner as to prevent the screw from working loose, and the screw is formed with one end split transversely thus setting up two ears which, when the screw is seated in the door knob shank and extended through the spindle, will 20 spread between the shaft and shank of the door knob and thus lock itself securely in position.

The invention will be best understood 25 from a consideration of the following detailed description taken in connection with the accompanying drawing forming a part of this specification, with the understanding that the invention is not confined to any strict conformity with the showing of the 30 drawing, but may be changed and modified so long as such changes and modifications mark no material departure from the salient features of the invention as expressed in the appended claim.

35 In the drawing:—

Figure 1 shows a door knob and a portion of a shaft, in side elevation, the knob shank and shaft adjacent thereto being in section to show the screw embodying this invention 40 in position.

Figure 2 is a transverse section taken upon line 2—2 of Figure 1.

Figure 3 is a detailed perspective view of the screw embodying this invention and, 45

Figure 4 is an enlarged side elevation of the screw embodying this invention.

Referring now to the drawing in detail 50 wherein like numerals of reference indicate corresponding parts throughout the several views, the numeral 1 indicates a door knob of ordinary construction and having the usual shank portion 2 which is provided with a longitudinal passage 3 into which

passage the lock actuating spindle 4 is adapted to have one end extended, as shown. 55

Extending transversely of the shank 2 and opening into the central passage 3 formed therein, is a threaded screw passage 5 into which the usual securing screw is extended to pass through a similarly threaded passage 6 which is formed transversely through the spindle 4 adjacent one end thereof. As is well known the shank passage 3 is usually of materially greater cross sectional area than is necessary to 60 take the end of the spindle 4, and due to this manner of constructing, the screw embodying this invention is enabled to lock itself in position after having been threaded into the passages 5 and 6, as will be hereinafter described.

The screw embodying this invention is indicated by the numeral 7 and a headless type is shown which is provided with threads throughout its length, but it is understood 65 that a headed screw may also be employed.

One end of this screw 7 is provided with the usual kerf 8 to receive the end of a screw driver when the screw is being placed 70 in position.

The opposite end of the screw body 7 is transversely slotted as at 9, and the side walls of this slotted portion are curved toward the side of the screw body, at the 75 end of the screw as indicated at 10 thus forming the inner end of the screw with a pair of oppositely positioned tapered tongue portions 11.

These screws are usually of soft metal 80 construction, being usually turned from brass and as will be readily apparent, when the screw is driven into the passages 5 and 6 and the tapered ends of the tongues 11 contact with the opposite wall of the passage 3 in the shank 2, these tongues will 85 be forced to spread outwardly as indicated in Figure 1, forcing themselves into the slight space which is to be found between one side of the spindle 4 and the adjacent wall of the passage 3.

100 It will thus be seen from the foregoing description that the screw 7 after having been driven into the passages 5 and 6 as shown in Figures 1 and 2, will act to lock itself in position and thus the usual annoying loosening of the door knob upon the 105

spindle 4 due to the loosening or loss of the usual screw which holds the door knob in position upon the spindle, will be avoided.

Having thus described my invention what

5 I claim is:—

In a device of the character described, including a door knob having a shank provided with a longitudinally extending bore to receive the transversely apertured end of 10 a shaft and further having a threaded passage extending through the shank and terminating in said bore, a screw body thread-

ed throughout and having one end bifurcated, the furcations of said bifurcated end being each curved upon its inner side only 15 from the inner to the outer ends thereof, the tips of said furcations being designed to spread laterally upon forced contact with the inner wall of said bore after being extended through the threaded passage and 20 apertured end of said shaft.

In testimony whereof, I affix my signature hereto.

ARCHIBALD M. ESTABROOK.
